POWER SUPPLY ARRANGEMENT SUITABLE
FOR USE IN TELEPHONE SYSTEMS

Rudolph Frank Stehlik, Antwerp, Belgium; assignor to Associated Telephone & Telegraph Company, Chicago, Ill., a corporation of Delaware

Application September 12, 1938; Serial No. 229,487
In Great Britain September 21, 1937

3. Claims. (Cl. 179—77)

The present invention relates to power supply arrangements suitable for use in telephone systems and is more particularly concerned with arrangements for giving a suitable current supply to a small private telephone system which may or may not be connected with the public exchange system. The object of the invention is to provide a compact piece of equipment suitable for use in connecting to the mains without the need for batteries and the like, and suitable also for use with either alternating or direct current and for a wide variety of mains voltages.

According to one feature of the invention in a power supply arrangement suitable for use in a telephone system, the converting equipment is adaptable for operation by either alternating or direct current by the alteration of the connections on a terminal block, the connections for direct current operation bringing into action a vibrator by means of which pulsating current is fed to a transformer which in the case of the connections for alternating current operation is fed directly from the mains.

According to another feature of the invention in a power supply arrangement suitable for use in a telephone system, the commercial supply mains are connected to a transformer the output of which is rectified, a separate winding on the transformer being employed to provide ringing current.

A further feature of the invention is that in a power supply arrangement suitable for use in a telephone system, a vibrator operated from commercial direct current supply mains provides pulsating current which is fed to a transformer to give alternating current of the appropriate voltage which is subsequently rectified to give the direct current required for operating the telephone equipment.

The invention will be better understood from the following description of a preferred method of carrying it into effect which should be taken in conjunction with the accompanying drawing comprising Figs. 1-3. Fig. 1 is a circuit diagram of the complete power supply unit, while Figs. 2 and 3 show respectively the connections which are made on the terminal block in the case of direct and alternating current respectively.

Considering first the case of direct current operation with a supply at 220 volts when the upper set of connections in Fig. 2 will apply, it will be seen that from the right-hand supply terminal the circuit extends by way of resistance R10 to terminal 8, thence by way of cross connections to terminal 6 and tapping point F on

the primary of the transformer T, while from the left-hand terminal of the supply the circuit extends over resistances R2 and R3 in parallel, winding of the vibrator or pole-changer PC, terminal 5; cross connection to terminal 7 and tapping point G of the transformer T. The coil of the vibrator PC is energised in this circuit including the portion FG of the transformer primary winding and it attracts its armature thereby short-circuiting itself so that the vibrating armature is released and then engages its back contact and is maintained in operation in well-known manner. It will be appreciated that when the vibrating armature engages its lower contact the left-hand terminal of the supply is extended direct to tapping point G, while when it engages its upper contact this terminal is extended to tapping point A. The primary of the transformer thus operates on a center tapped basis, the center point being the tapping point F which is connected over resistance R10 to the right-hand supply terminal. In these circumstances due to the movement of the vibrating armature a pulsating current passes through the primary of the transformer and generates a suitable alternating current in the secondary.

It will be seen that the transformer has two secondary windings one of which EJ is connected to earth and extends to terminal RL from which ringing current is supplied to the telephone equipment. The other secondary winding KLM, the whole of which is connected up in this case by the strapping of terminals 13 and 15, extends to a full wave rectifier R, preferably of the dry contact type whereby direct current is supplied to terminals B and E representing battery and earth respectively for the current supply to the exchange equipment. The earth lead from the rectifier to terminal E includes a choke CH which is shunted by the two large capacity electrolytic condensers E1 and E2, the junction point of these condensers being connected to the battery lead extending to terminal B. This forms a smoothing arrangement in accordance with well-known principles.

Since in these circumstances the vibrator or pole changer is in constant operation, it is desirable that special mounting arrangements shall be provided in order to ensure that its operation shall not produce undue noise, since in the circumstances in which a private telephone exchange is often used, the unit might be mounted in a room in which quiet was essential. The obvious need is to enclose the unit in a sound-proof casing but when this is done difficulties

arise in providing for satisfactory heat dissipation without making the equipment unduly bulky. According to a subsidiary feature of the invention this difficulty is overcome by resiliently mounting the pole changer in a solid metal casting. By this means the noise of operation is practically eliminated and the casting permits the adequate dissipation of heat. The thickness and nature of the metal casting are important and it has been found that the best results are obtained when this is constructed of aluminium from $\frac{3}{8}$ " to $\frac{1}{2}$ " thick.

It will be seen that when the direct current supply has a voltage of 110 instead of 220, the strapping connections made on the terminal block are slightly different as shown in the lower portion of Fig. 2. The strapping of terminals 1 and 2 has the effect of short-circuiting resistances R_2 and R_3 so that adequate current is provided at the lower voltage for maintaining the operation on the pole changer PC. Moreover terminal 5 is connected to terminal 6 and terminal 8 is connected to terminal 10 so that the portion of the primary of the transformer T which is used is the portion AF, the tapping point C being used as the centre point.

In order that the power supply unit shall be capable of providing a heavy current in certain circumstances while having comparatively low no load losses, it is provided that when a heavy current is required, for instance when switches are stepping or when a call to another exchange has been set up, relay RD is operated by the connection of earth to the associated terminal and thereupon resistance R_{10} is short-circuited. By this means the unit is enabled to deliver a heavy current at need while the losses when the system is not in use are negligible. The condensers C_1 and C_2 connected across the supply with their junction point earthed are to prevent the equipment from having any deleterious effect on other consuming devices connected to the supply.

When the supply is alternating current, the connections on the terminal block are as shown in Fig. 3, the upper connections being made in every case and the lower connections in accordance with the voltage indicated. It will be seen that in this case the supply mains are connected straight through to the primary of the transformer, different tappings of which are employed in accordance with the mains voltage. It is desirable also in this case to employ only the portion KL of the secondary winding which feeds the rectifier and this is taken care of by strapping terminals 14 and 15. In these circumstances it will be appreciated that the vibrator is not set in operation and that the condensers C_1-C_7 and resistances R_1 and R_4-R_9 which are provided on the primary side for smoothing and blocking purposes are no longer required.

I claim:

1. In a telephone system power supply unit, a transformer having a primary winding and secondary windings, a supply circuit adapted to be connected with a source of either direct or alternating current, circuit connections including at least a portion of said primary winding, a vibrator for alternately closing said circuit connections when the said supply circuit is connected

to a source of direct current, and a terminal block whereby the said circuit connections may be altered to short circuit said vibrator when said supply circuit is connected to a source of alternating current, output terminals, a rectifier bridge, one of said secondary windings connected to a circuit including said rectifier bridge and a pair of said output terminals whereby the alternating current induced in said one secondary winding is rectified to thereby provide a source of direct current at said pair of output terminals for satisfactory operation of telephone equipment, said other secondary winding connected in circuit with another of said output terminals to provide a source of alternating current satisfactory as a ringing current supply for telephone equipment.

2. In a telephone system power supply unit, a transformer primary winding, input terminals for connecting said unit to a commercial source of power of either direct or alternating current, a vibrator adapted for operation by direct current, a terminal block, circuit connections from said primary winding and said vibrator to said terminal block, said terminal block provided for jumpering said circuit connections to connect said vibrator and said primary winding to said input terminals to operate said vibrator and thereby feed a pulsating current to said primary winding when direct current commercial power is connected thereto and for jumpering said circuit connections to connect said primary winding to said input terminals direct to feed alternating current to said primary winding when alternating current commercial power is connected thereto, a two winding secondary for said transformer, output terminals, a rectifier bridge, one of said secondary windings and said rectifier bridge connected to said output terminals whereby the alternating current induced into said secondary winding from said primary winding by transformer action is rectified to supply said output terminals with direct current suitable for operation of telephone equipment, and the other winding of said secondary providing an alternating current source for use as ringing current for telephone systems.

3. In a telephone system power supply unit, a transformer having a primary winding and a secondary winding, a vibrator, input terminals adapted to be connected to a source of direct current, an input circuit including said input terminals, said vibrator and said primary winding whereby said vibrator feeds a pulsating current through said primary winding when said input terminals are connected to a source of direct current, a resistance included in said circuit for reducing the current flowing through said primary winding, a rectifier bridge, an output circuit including said secondary winding and said bridge connected to a load requiring direct current, said rectifier bridge changing the alternating current induced into said secondary winding by transformer action into direct current, and means for automatically short circuiting said resistance to increase the current flowing in said primary winding when an increase direct current is required for said output circuit.
